UNITED STATES PATENT OFFICE.

JULIUS PEGEL, OF PHILADELPHIA, PENNSYLVANIA, ASSIGNOR TO JOHN BROMLEY & SONS, OF SAME PLACE.

DESIGN FOR A RUG.

SPECIFICATION forming part of Design No. 19,463, dated December 3, 1889.

Application filed November 7, 1889. Serial No. 329,586. Term of patent 3½ years.

To all whom it may concern:

Be it known that I, JULIUS PEGEL, a citizen of the United States, and a resident of Philadelphia, Pennsylvania, have invented 5 a new and Improved Design for Rugs, reference being had to the accompanying photographic illustration, making part hereof, in which—

A is the ground-work of the rug, which is 10 an oblong square; B, a middle oblong-square panel; C D E F, fern-leaves and clusters of flowers of fanciful and natural design set in the space around the panel B.

G G are flowers intruding upon the inner space of the panel; H, a spray or line of 15 flowers and leaves set diagonally across the inner space of the panel.

What I claim as new is—

The design for rugs, as shown.

In witness that the above is my invention 20 I have hereunto set my hand.

JULIUS PEGEL.
